ABIJAH L. KNIGHT, OF BALTIMORE, MARYLAND.

Letters Patent No. 70,863, dated November 12, 1867.

IMPROVED MACHINE FOR CUTTING PAPER-STOCK.

The Schedule referred to in these Letters Patent and making part of the same.

TO ALL WHOM IT MAY CONCERN:

Be it known that I, ABIJAH L. KNIGHT, of the city and county of Baltimore, and State of Maryland, have invented a new and improved Machine for Cutting Paper-Stock; and I do hereby declare the following to be a full, clear, and exact description of the same, reference being had to the accompanying drawings, forming part of this specification, and in which—

Figure 1 is a side elevation of my machine.

Figure 2 is a front end elevation of the same.

Figure 3 is a section of a detached portion of the frame, showing the knife *i*, block *H*, guide-frame *I*, and knives *c c'*.

Similar letters of reference indicate corresponding parts in the several figures.

In this invention the rags are fed to a vertically cutting knife, by means of a combination of smooth and fluted rollers to which an intermittent motion is imparted.

In the course of many years in which I have been engaged in the manufacture of paper, I have never observed a machine in operation which would cut the stock satisfactorily. The machines in use in this country and in Europe, all have knives attached to a revolving cylinder, and are obliged to be fed by hand. Their construction is such that the knives revolving with great velocity, and working upon the hard material, require an immense power to drive them, and run with so much clatter and noise as to become almost a nuisance in a paper-making establishment, besides very frequently getting out of gear and breaking everything around them. Where one of the knives works on a cylinder, its edge must strike with great force close to the edge of the stationary bed-knife, and if either gets in the slightest degree awry, everything is smashed in an instant. Where the revolving knives strike with such force as it is indispensably necessary to give them in such machines, it is quite impossible to preserve the gear from wearing and becoming disarranged, and such accidents as are above referred to are of very frequent occurrence in every paper-mill now in operation. Besides this, the revolving knives cannot be kept sharp by grinding them. Every little while they have to be taken out of the machine and upset by a smith, another set meanwhile taking their place or the machine standing idle. The dust raised by the violent operation of these machines, too, is so great that the common practice is for the workmen to have sponges bound over their faces to protect their respiratory organs while at work with the rag-cutters. Another and serious defect of the machine in present use is that it does not cut the stock clean, but through the slightest and almost constant derangement of the knives the material is pounded rather than cut in pieces, hence shreds and lint are produced, which in the subsequent process of forming pulp are boiled, washed, and wasted away, while in my machine the cut is direct, certain, and clean, thereby saving considerably. Paper-makers have long desired a machine in which these defects would be obviated, but none has hitherto been invented and brought into use. The machine which I have invented for that purpose has now been on trial at a paper-mill near Baltimore for several months, and is found to work perfectly, cutting the rags with less than half the power required to operate the old one, working silently, and raising so little dust as not at all to incommode the employés. It runs evenly and regularly, never getting out of gear, and its knives, when dull, can be put in perfect working operation in a few minutes by grinding them.

In order that others skilled in the art to which my invention appertains may be enabled to make and use the same, I will proceed to describe it in detail.

In the drawings, *A A* represent the two stout forward posts of my machine, connected together by cross-beams *B B*, and with the rear posts *A' A'* by the side beams *B' B'*. *B² B²* are cross-beams connecting together the two rear posts. The whole frame thus constructed supports a horizontal feed-table, *T*, the forward end of the floor of which comes out flush with the front side of the posts *A A*, and is fitted with the sharp, stout bed-knife *C*. The latter may be constructed in two pieces, one, *c*, vertical, and attached to the front edge of the feed-table, and the other, *c'*, if used, horizontal, lying flat on the floor of the feed-table to which it is attached by set-screws, and having its edge extending along close to the edge of the vertical knife *c*, so as to support and strengthen it. Perhaps in such a construction it might be more proper to call the vertical knife *c* the knife, and the horizontal knife simply a supporting plate to steady the edge of the knife.

D is the main working shaft of the machine, by which the power is applied at D', and communicated to the secondary working shaft G through gear-wheels d d'. From the shaft G the power is directly applied to the movable knife and the feeding apparatus, as hereafter described. The shaft D bears in boxes fixed to the upper side of the beams B¹ B¹, and the shaft G in boxes fixed to the front side of the posts A A, a little above the point where the side beams are attached to them. The pinion d may be small compared with the pinion d', since it is not necessary to gain velocity, but, on the other hand, the power can be economized.

The shaft G is provided with a crank, E, at each extremity, which works pitmen F F, connected with the ends of the knife-block H, and vibrating it vertically as the shaft G revolves. The knife-block runs in a stout guiding-frame, I, and is itself provided with shoulders or vertical guide-cleats h h, to steady and direct it in the frame. The knife i is a sharp blade attached to the inner side of the block H, so as to come out flush with it, and bevelled from the front to an edge. It may be attached to the block by set-screws by which its cut can be regulated, or by which, when its edge is ground away, it can be set down a little so as to keep the proper position. The bed-knife C may also be attached to the feed-table floor in the same manner, for the same purpose.

The edge of the knife i cuts close against the edge of the bed-knife, both operating together to sever the rags. The edge of the vibrating knife is slightly inclined from one end to the other, to make it cut more easily. Its ends may extend beyond the inner edges of the posts A A if thought desirable, in order to steady the blade. A chute or apron may be provided under the knife-block and over the pinion d', into which the rags will fall when cut, and which will deliver them at the side or in front of the machine.

The feeding attachment consists of four rollers, two fluted ones, M M', working across the top of the feed-table, and two smooth ones, N N', working across the feed-table under it, but so that their upper sides project slightly above its floor in transverse apertures made through the floor for the purpose. Motion is communicated to them all from the shaft G and pitman F, by means of a long lever, L, pivoted on a short arm, K, projecting laterally from the rear post A'. The forward end of this lever is struck and lifted after every stroke of the knife i by a pin, e, fixed to the pitman, and when the pitman descends the lever L falls back by its own weight. The pin e may be made adjustable on the pitman, if necessary, in order to regulate the length of stroke of the lever, and by consequence the feed of the machine.

The lever thus operated is provided with a pawl or dog, p, working in a ratchet, r, on the side of the machine, and moving the ratchet-wheel round more or less at every stroke of the piston, according as the pin e is in position to give the full stroke or only a part of the stroke to the lever L. The ratchet has a pinion-wheel, n', fixed to its inner side, revolving on the same shaft with it, namely, the shaft of the forward smooth roller N', which works an idle-wheel, O, which in its turn works the rear smooth roller by means of a pinion, n, and works both of the fluted rollers by means of a second idle-wheel, O', gearing with the respective pinions m and m' of the two upper rollers. In this way the proper direction is given to the motion of each of the feed-rollers, and all the rollers are made to move together and carry the rags forward at the moment when the knife has finished its stroke and has ascended to prepare for another.

The machine would frequently become choked if the upper rollers worked in fixed bearings like the lower rollers, and accordingly I have provided movable bearings for them. I make them each bear in a frame, P, hinged at one side to the top of the side walls of the feed-table, as shown at q, by which arrangement the fluted rollers will ride over any temporary jam of material that may happen to accumulate or become knotted and twisted together at any particular point, and when the obstacle is past the rollers will by their own weight resume their place. The rollers are all of wood. The rest of the machine is preferably constructed of iron.

In the machine which is now working admirably in a manufactory, I use a knife twelve inches in length, with a seven-inch stroke. Running at the rate of forty strokes a minute, the average speed which I give it, will cut seven hundred pounds of rags per hour, creating but little dust or noise, and working perfectly in every particular. No one is required to feed the rags to the machine, it performing that work itself, with the utmost regularity.

Such a machine as I have described is made at comparatively small expense, and by its superior economy in the matters of running without repairs, and in requiring a less number of workmen to work it, will pay for itself in a short time. It can be run with less than one-half the power required to run the old machines.

Having thus described my invention, what I claim as new, and desire to secure by Letters Patent, is—

1. The combination of the crank-shaft G, pitmen F F, knife-block H, guide-frame I, and knives i and C, substantially as and for the purpose specified.

2. The combination of the crank-shaft G, pitman F, having the pin e, lever L, pawl p, ratchet r, idle-wheels O and P, feed-rollers M M', N N', and feed-table T, all constructed and arranged substantially as and for the purpose set forth.

3. The paper-stock-cutting machine above described, consisting of the parts specified in clauses one and two of this claim, combined and arranged together substantially as described, for the purpose of cutting and preparing paper-stock.

To the above specification of my improvement I have signed my hand this sixteenth day of July, 1867.

A. L. KNIGHT.
